UNITED STATES PATENT OFFICE.

HARRY L. BUSKEY, OF ARCADIA, FLORIDA.

DESIGN FOR AN ORNAMENT FOR THE BELL OF A HORN.

Application filed August 21, 1925. Serial No. 14,549. Term of patent 3½ years.

To all whom it may concern:

Be it known that I, HARRY L. BUSKEY, a citizen of the United States, residing at Arcadia, in the county of De Soto and State of Florida, have invented a new, original, and ornamental Design for Ornament for the Bell of a Horn, of which the following is a specification, reference being had to the accompanying drawing, forming a part thereof.

The figure is a plan view of the ornament showing a segment in completed form and the remaining portion of the ornament in diagrammatic outline.

I claim:

The ornamental design for an ornament for the bell of a horn, as shown.

H. L. BUSKEY.
